Primary Examiner — Ruth McInroy*(74) Attorney, Agent, or Firm* — Erickson Law Group, PC(57) **CLAIM**

We claim the ornamental design for a helmet jaw guard, as shown and described.

DESCRIPTION

FIG. 1 is a perspective view of a helmet jaw guard;
 FIG. 2 is a right side view of the helmet jaw guard;
 FIG. 3 is a left side view of the helmet jaw guard;
 FIG. 4 is a rear view of the helmet jaw guard;
 FIG. 5 is a front view of the helmet jaw guard;
 FIG. 6 is a top view of the helmet jaw guard;
 FIG. 7 is a bottom view of the helmet jaw guard; and,
 FIG. 8 is a perspective view thereof; the helmet shown in broken lines forms no part of the claimed design.
